[57] CLAIM

The ornamental design for a compact pump unit for enteral delivery, as shown and described.

DESCRIPTION

FIG. 1 is a front right perspective view of a compact pump unit for enteral fluid delivery, showing my new design;

FIG. 2 is a front elevational view thereof;

FIG. 3 is a right side elevational view thereof, with a cassette loaded in the pumping chamber;

FIG. 4 is a left side elevational view thereof, with the cassette removed;

FIG. 5 is a left side elevational view thereof;

FIG. 6 is a rear elevational view thereof;

FIG. 7 is a top plan view thereof; and

FIG. 8 is a bottom plan view thereof.
